(57) **CLAIM**

The ornamental design for a quadrant dental articulator pin locator, as shown and described.

DESCRIPTION

FIG. 1 is a top and front top perspective view of a quadrant dental articulator pin locator showing my new design;

FIG. 2 is a top and rear perspective view thereof;

FIG. 3 is a bottom and front perspective view thereof;

FIG. 4 is a bottom and rear perspective view thereof;

FIG. 5 is a left side elevation thereof;

FIG. 6 is a right side elevation thereof;

FIG. 7 is a bottom plan view thereof;

FIG. 8 is a top plan view thereof;

FIG. 9 is a front elevation thereof;

FIG. 10 is a rear elevation thereof;

FIG. 11 is a front and bottom perspective view of a modified embodiment of the design shown in FIGS. 1 through 10;

FIG. 12 is a rear and bottom perspective view thereof;

FIG. 13 is a front and top perspective view thereof;

FIG. 14 is a top and rear perspective view thereof;

FIG. 15 is a left side elevation thereof;

FIG. 16 is a right side elevation thereof;

FIG. 17 is a bottom plan view thereof;

FIG. 18 is a top plan view thereof;

FIG. 19 is a front elevation thereof; and,

FIG. 20 is a rear elevation thereof.

The broken lines showing of portions of the claimed design and the modified embodiment thereof are included for the purpose of illustrating environmental structures and form no part of the claimed design.
